US0D1107163S

(12) **United States Design Patent** (10) **Patent No.:** **US D1,107,163 S**
(45) **Date of Patent:** **** Dec. 23, 2025**

(54) **SUPPRESSOR MOUNT**

(71) Applicant: **WHG PROPERTIES, LLC**, North Wales, PA (US)

(72) Inventors: **Frank E. Robinson**, Schwenksville, PA (US); **William H. Geissele**, Lower Gwynedd (PA)

(73) Assignee: **WHG PROPERTIES, LLC**, North Wales, PA (US)

(**) Term: **15 Years**

(21) Appl. No.: **29/953,093**

(22) Filed: **Jul. 19, 2024**

(51) **LOC (15) Cl.** **22-01**

(52) **U.S. Cl.**

USPC **D22/108**

(58) **Field of Classification Search**

USPC D22/104, 108, 199

CPC F41A 21/02; F41A 21/38; F41A 21/30

See application file for complete search history.

(57) **CLAIM**

The ornamental design for a suppressor mount as shown and described.

DESCRIPTION

FIG. 1 is a perspective view of a suppressor mount showing the new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a cross-section bottom plan view thereof, taken along line 9-9 of FIG. 3.

The broken lines depict features of the suppressor mount that form no part of the claimed design.

1 Claim, 6 Drawing Sheets
